UNITED STATES PATENT OFFICE.

JOHN M. BYRON, OF BOSTON, MASSACHUSETTS, ASSIGNOR TO THE ROGERS LIQUID METER COMPANY, OF SAME PLACE AND PORTLAND, MAINE.

METER-REGISTERING DEVICE.

SPECIFICATION forming part of Letters Patent No. 633,567, dated September 26, 1899.

Application filed September 7, 1898. Serial No. 690,414. (No model.)

To all whom it may concern:

Be it known that I, JOHN M. BYRON, of Boston, in the county of Suffolk and State of Massachusetts, have invented certain new and useful Improvements in Meter-Registering Devices, of which the following, taken in connection with the accompanying drawings, is a specification.

My invention relates to meter-registering devices, and has for its object the registering of the work being done by a water or other meter at any desirable point at a distance therefrom; and it consists in certain novel features of construction, arrangement, and combination of parts, which will be readily understood by reference to the description of the accompanying drawings and to the claim hereunto appended, and in which my invention is clearly pointed out.

20 Figure 1 of the accompanying drawings illustrates my invention as applied to the Rogers water-meter shown and described in Letters Patent No. 458,739, issued to Richard J. Rogers September 1, 1891. Fig. 2 is a central longitudinal section through the cylinder and its casing in a horizontal plane, and Fig. 3 is a vertical longitudinal section through the center of the casing and showing the oscillating cylinder in elevation.

25 In the drawings, A is the oscillating cylinder, provided with suitable trunnions A' and A'', by which it is mounted in bearings in the fixed casing B, one head of which is removed in Fig. 1 in order to show the cylinder.

30 The cylinder A has formed thereon or secured thereto at the center of its length and on its upper side the forked lug a, which engages the movable end of the arm b, firmly secured upon the inner end of the vertical shaft c, mounted in a suitable packed bearing in the casing B, substantially as in said cited patent.

35 The upper end of the shaft c has firmly secured thereon the arm d, to the free end of which is pivoted the pawl e, which engages the teeth of the ratchet-wheel C to impart thereto an intermittent rotary motion, moving it one tooth at each double oscillation of the cylinder and through such motion operating the train of gearing and the several reg-

istering-indexes f f, carried by the plates g and g', all in a well-known manner.

In other styles of meters the necessary movement is imparted to the arm d from the movements of the piston in a variety of ways, but all producing substantially the same result of imparting an intermittent vibratory movement thereto, and thereby causing an intermittent rotary movement to be imparted to the ratchet-wheel C and its shaft, whereby the several index-fingers of the register are moved at their proper relative speeds in a well-known manner.

In carrying out my invention I secure to the casing of the meter, but insulated therefrom, the screw-cup h and the yielding electrode i and set in the under side of the wheel C the contact pin or electrode j, which as said wheel is revolved comes in contact with the electrode i to close an electric circuit and passing it breaks the circuit.

40 D is a registering mechanism of any suitable and well-known construction located at any desired distance from the meter, said registering mechanism being shown only in rear elevation and is provided with the ratchet-wheel E on its initial or operating shaft h.

F is a magnet connected by the conducting-wire l through the metal of the meter or the register thereon to the electrode j by the wire m to one pole of the battery G or other source of electric energy, the other pole of said source of electric energy being connected to the screw-cup h by the conducting-wire n.

45 H is the armature of the magnet F, attached to the pivoted arm or lever I, to the upper end of which is pivoted one end of the pawl J, the opposite end of which engages the teeth of the ratchet-wheel E, as shown.

The operation of my invention is as follows: As the wheel C is rotated by the action thereon of the pawl e the pin j comes in contact with the electrode i and closes the electric circuit, which renders the electromagnet F operative, and the armature is attracted to the poles of the magnet, thereby moving the pawl J toward the right and moving the ratchet-wheel E about its axis at each move-

85

100

ment of the armature toward the magnet a distance equal to the length of a tooth of the ratchet-wheel E, which must be of such length that at each attraction of the armature the 5 wheel E will move through one-tenth of a revolution, and the wheel E will make a complete revolution in the same time that the wheel C makes ten revolutions, and it therefore follows that if one revolution of the index-finger carried by the shaft on which the 10 ratchet-wheel C is mounted indicates that one foot of liquid has passed through the meter one revolution of the index-finger carried by the shaft k, which carries the ratchet-wheel 15 E, indicates that ten feet of liquid have passed through the meter. A spring S is secured by one end to the arm I and by its other to some fixed object, as the upright U, and acts to retract the armature when the circuit is 20 broken and cause the pawl J to engage another tooth of the ratchet-wheel E.

The register mounted directly upon the meter-casing may be used as shown, if desired, or it may be entirely dispensed with, 25 only retaining the shaft c, arms b and d, and the ratchet-wheel C and pawl e without departing from my invention.

My invention is of great advantage in that the register may be located in the most convenient and desirable location in the building, where it is easily accessible for examination at any time, while the meter, especially 30 if a water-meter, is very liable to be placed

in the basement or cellar in an inconvenient or not easily-accessible position.

35

What I claim as new, and desire to secure by Letters Patent of the United States, is—

The combination with a liquid-meter having an oscillating cylinder, of the oscillating shaft c; the arms b and d secured on said shaft; the lug a projecting upward from said cylinder and engaging the arm b; the pawl e carried by the arm d; the ratchet-wheel C mounted upon a vertical revoluble shaft, and provided with the pin j; a registering mechanism connected to and operated directly by the rotation of said shaft; a yielding electrode in position to be contacted by said pin j, but insulated from the meter; a registering mechanism located at a distance from 45 said meter; an electromagnet in proximity to said distant registering mechanism; an armature controlled by said magnet; an electric circuit connecting said magnet and meter; and means connected to said armature 50 for imparting intermittent movements to said distant registering mechanism.

In testimony whereof I have signed my name to this specification, in the presence of two subscribing witnesses, on this 27th day 55 of August, A. D. 1898.

JOHN M. BYRON.
